(No Model.)

B. F. WILSON.

HOISTING BUCKET.

No. 363,105.

Patented May 17, 1887.

UNITED STATES PATENT OFFICE.

BENJAMIN F. WILSON, OF PITTSBURG, PENNSYLVANIA.

HOISTING-BUCKET.

SPECIFICATION forming part of Letters Patent No. 363,105, dated May 17, 1887.

Application filed October 18, 1886. Serial No. 216,599. (No model.)

To all whom it may concern:

Be it known that I, BENJAMIN F. WILSON, a citizen of the United States, residing at Pittsburgh, in the county of Allegheny and State of Pennsylvania, have invented certain new and useful Improvements in Hoisting-Buckets; and I do hereby declare the following to be a full, clear, and exact description of the invention, such as will enable others skilled in the art to 5 know which it pertains to make and use the same, reference being had to the accompanying drawings, which form a part of this specification.

My invention relates to an improvement in 15 hoisting-buckets for loading, unloading, and transporting coal.

The object is to provide a means whereby coal or other substance may be loaded or un-loaded from boats, cars, &c., without break-age. This I accomplish with two open-ended 20 boxes hinged together and provided with a means for attachment to a hoisting device, together with certain other details of construction and combination of parts, as will be fully 25 described hereinafter.

In the accompanying drawings, Figure 1 is 30 a side elevation of an improved hoisting-box constructed in accordance with my invention. Fig. 2 is a sectional end elevation of the same, taken on the line $x-x$ of Fig. 1, looking toward the left. Fig. 3 is a side elevation of my improved box, showing the position of the same while in the act of discharging its contents.

To put my invention into practice, I provide 35 two strong wooden boxes, a and b , each having an open top and end, and securely braced with three metallic bands, two of which, c , are riveted or bolted to the ends and bottom, and the other, d , placed at right angles, 40 bracing the sides and bottom of the box. These boxes a and b , I secure together by means of a strong hinge, e , placed on each of the upper corners of the open ends of the boxes. At 45 about one-third of the distance between the hinges e and outer edges of the boxes a and b are four circular openings, f , in which short chains g , provided with hooks h , are connected to the boxes. These chains g , I secure 50 at their other ends to a ring, i , which I connect to a hoisting device capable of elevating the boxes a and b to any required height. At

the two ends of the boxes a and b , I form two circular openings, k , and connect the same by chains l to the hoisting device, in the same 55 manner as before described. These boxes a and b , constructed as described, are filled with coal or other substance, and packed in cars or boats for transportation and unloaded by a crane or hoisting device.

The operation of unloading is as follows: The four short chains g , intended for lifting the boxes, are attached to a hoisting device such as is in common use at all points of delivery, and by means of the hooks h are secured in the openings f nearest the hinges e , and being to one side of the center of each of the boxes a and b will not allow the same to open or spread. The end chains, l , are also attached to the boxes in the same manner, but 60 lead to an independent drum on the hoisting apparatus. The boxes and contents are now elevated and moved to the desired point of unloading and lowered to the floor or ground. The ends of the boxes a and b are now ele- 65 vated by means of the chains l , which operation gently discharges the contents toward each other, substantially lifting the boxes from beneath their burden. The chains g and l are now detached from their boxes and secured to another. This operation is continued 70 until the vehicle is unloaded.

Having thus described my invention, what I claim, and desire to secure by Letters Patent, is—

The improved hoisting apparatus herein described, comprising, essentially, the two rectangular parts hinged together at their meeting ends at their tops, the metallic straps c , having their vertical branches terminating 85 in eyes, as shown, the straps d , placed at right angles to the straps c , the hinges at the upper open ends of the said parts having the eyes f at their outer ends, the set of chains g , connected together at their upper ends and secured to the eyes f at their lower ends, and the set of chains l , connected at their upper ends and secured to the eyes of the straps c at their lower ends, substantially as specified.

BENJAMIN F. WILSON.
